UNITED STATES PATENT OFFICE.

WILBUR L. SPADE, OF O'FALLON, ILLINOIS.

CAMPER'S-OUTFIT BOX.

1,002,537.

Specification of Letters Patent. Patented Sept. 12, 1911.

Application filed June 6, 1910. Serial No. 565,383.

To all whom it may concern:

Be it known that I, WILBUR L. SPADE, a citizen of the United States, and resident of O'Fallon, St. Clair county, Illinois, have invented certain new and useful Improvements in Camper's-Outfit Boxes, of which the following is a specification containing a full, clear, and exact description, reference being had to the accompanying drawings, forming a part hereof.

My invention relates to improvements in camper's outfit boxes, the object of my invention being to construct a box for containing a camper's outfit or the like, which box is separable and the parts shaped to form a folding table and benches.

For the above purposes my invention consists in certain novel features of construction and arrangement of parts as will be hereinafter more fully described, pointed out in the claims and illustrated by the accompanying drawings; in which:

Figure 1 is a perspective illustrating my invention in box form which box is primarily designed to contain a camper's outfit; Fig. 2 is a perspective illustrating a table formed from parts of the box; Fig. 3 is a perspective of one of the benches; Fig. 4 is an enlarged, detail elevation illustrating the manner of connecting the folding legs to the table leaves; Fig. 5 is an elevation illustrating the manner of hingedly connecting the leaves with the table top proper; and Fig. 6 is a transverse, sectional view of the box in a closed position.

Referring by numerals to the accompanying drawings: 1 designates the rear member of the box, the upper and lower margins of which are beveled on angles substantially forty five degrees.

2 designates the bottom of the box, the rear margin of which is beveled or cut at an angle of substantially forty five degrees.

3 designates the top of the box, the rear margin of which is beveled or cut at an angle of substantially forty five degrees.

The rearmost margins of the bottom and top are secured to the rear member by the hinges 4.

5 designates the lower half of the front of the box and 6 the upper half of the front of the box.

7 designates members constituting the major portions of the ends of the box, each of which is provided with extensions 8 of its upper and lower margins and 9 designates integral, V-shaped projections of the members 7 lying between the extensions 8, the rearmost margins of the members 7 being securely fastened to the rear of the box flush with its ends.

10 designates members which are secured to the rear faces of the upper and lower halves of the front of the box, flush with their ends, and which members are shaped to conform with the members 7 and their extensions 8 and 9 which members constitute parts of the ends of the box.

Formed through the bottom and top of the box are the openings 11 and carried by the front members 5 and 6 are the staples 12, the openings 11 and staples 12 alining vertically. Inserted through said openings and staples is a headed rod 13 having an eye at its upper end, through which is placed the locking bolt of a lock 14. In this manner the parts are held in box form.

15 and 16 designate legs hingedly secured to the bottom and top respectively, each of which is provided with a jointed brace 17 secured at one end to one of the legs and at the opposite end to the bottom or top.

18 designates hooks carried by the bottom and top for holding the legs in place against the inner faces of the bottom and top.

The box as shown and described may be employed to receive such articles which go to make up a camper's outfit and, if desired, there may be handles secured to the ends for the handling or carrying of the box.

Ordinarily, a container for a camper's outfit has no useful function other than a container. By constructing the box as I have done there may be formed a complete folding table, for dining or other purposes, having folding leaves with supports therefor and a pair of benches to be employed in connection with the table. The rear of the box forms the table top proper, the bottom and top of the box forming the table leaves, while the members 7, constituting parts of the ends of the box, with their marginal extensions 8 constitute supports for the table top proper and the legs 16 are arranged to support the table leaves. The upper and lower halves of the front of the box with the parts 10 of the ends of the box form separate benches as shown in Fig. 3.

I claim:

1. In a camper's outfit box, the combination with a back and a top and bottom hingedly connected with the back, of end

members rigidly secured to the back and having cut away portions, and a two-part front having right angled members arranged to conform with the cut away portions of said ends, said two-part front and the right angled members being separable from the back and the top and bottom, for the purposes stated.

2. In a camper's outfit box, the combination with a back and a top and bottom hingedly connected with the back, of end members rigidly secured to the back and having cut away portions, a two-part front having right angled members arranged to conform with the cut away portions of said ends, and legs hinged to the top and cover, said two-part front and the right angled members being separable from the back and the top and bottom, for the purposes stated.

3. In a camper's outfit box, the combination with a back and a top and bottom hingedly connected with the back, and end members rigidly secured to the back, at right angles thereto, and having cut away portions, of a two-part front having right angled members arranged to nest in the cut away portions of said ends, hinged legs secured to the top and bottom, and means for holding the parts of the box proper in box form, the two-part front and the right angled members carried thereby being separable from the remaining parts, for the purposes stated.

In testimony whereof, I have signed my name to this specification, in presence of two subscribing witnesses.

WILBUR L. SPADE.

Witnesses:

E. E. LONGAN,
E. L. WALLACE.
